UNITED STATES PATENT OFFICE.

JOSEPH WALTER FLAGG, OF WORCESTER, MASSACHUSETTS.

AUTOMATIC CASH-CARRIER.

SPECIFICATION forming part of Letters Patent No. 308,033, dated November 11, 1884.

Application filed June 20, 1884. (No model.)

To all whom it may concern:

Be it known that I, JOSEPH WALTER FLAGG, a citizen of the United States, residing at Worcester, in the county of Worcester and State 5 of Massachusetts, have invented a new and useful Improvement in Automatic Cash-Carriers, of which the following is a specification, illustrated by the accompanying drawings, in which—

10 Figure 1 shows a sectional view of the two hemispheres A and B, forming my carrier, the sections taken on lines X X and S S, Figs. 4 and 5. Fig. 2 is a detached sectional view of the metallic tube in the hemisphere B; Fig. 3, 15 a similar view of the tube in A. Figs. 4 and 5 are plan views of the hemispheres A and B.

Similar letters refer to similar parts in the several views.

My invention relates to the cash-carrier, and 20 is an improvement upon the carrier which formed the subject of Letters Patent No. 277,892, granted to me May 22, 1883, to which reference may be had for a general description of the carrier.

25 A and B denote the two hemispheres forming a spherical carrier, each having an outer and inner tube, *a b* and *f g*, and central elastic diaphragms, *e* and *h*, as described in the Letters Patent above referred to. In my present 30 invention the outer tube, *a*, in the hemisphere A has a flange, *a'*, both in one piece, the flange *a'* recessed in the plane face of the hemisphere A, resting on a seat or shelf, and is attached by screws *k k*, and the outer tube, *f*, in the hemisphere B has a similar flange recessed in the 35 plane surface of the hemisphere B both in one piece, and attached by the screws *k'*.

To the flange *a'*, I attach the spring-catches *c c*, and around the outer tube, *f*, I form a 40 shoulder, *f'*, in proper position on the tube to receive the spring-catches *c c* and hold the plane surfaces of the two hemispheres firmly in contact. The end of the tube *f* may be beveled, as at *f'*, allowing it to slide easily past 45 the beveled end of the spring-catches *c c*. The shoulder *f'* is cut away on opposite sides, as shown at *j j*, Fig. 5, in order to allow the catches to be removed and the hemispheres separated. The end of the tube *f* projects 50 beyond the diaphragm *h*, forming a cup or receptacle for the cash, the projecting end entering the opposite hemisphere A.

In the carrier shown and described in the Letters Patent No. 277,892, above referred to, the spring-catches were attached to the hemisphere carrying the projecting tube, and were made to enter the opposite hemisphere and engage a lip projecting inwardly from the shell of the carrier. This method of construction is subject to several objections. The 55 spring-catches had to be long enough to project beyond the plane surface of the hemisphere to which they were attached, so as to extend into the opposite hemisphere. This was a great disadvantage, as the projecting 60 springs were unsightly, and were liable to be loosened from the hemisphere by lateral strains at their ends, and the method of construction was expensive, as the lip had to be formed 65 separately from the tube. In my present form 70 the springs are entirely contained in the recess of the hemisphere to which they are attached. The lip *f'* may be formed at the same time the tube is made and at the same operation, effecting a saving, as found in practice, 75 of over one-half in the cost of making the carrier.

The only portion of the carrier in my present construction which projects beyond the plane surfaces of the hemispheres is the tube *f*, 80 which is rigidly attached to the hemisphere B, and, entering the recess in the opposite hemisphere A, serves as a guide to bring the two hemispheres concentric. In the form shown in Letters Patent No. 277,892 the projecting 85 springs were liable to become bent in using the carrier. In the application for Letters Patent filed by me April 5, 1884, Serial No. 126,798, the diaphragm-carrying tubes are held in a circular plate or disk recessed in the 90 plane surface of the hemispheres, the outer tubes being screwed into an opening in the center of the disks. In my present improved method of forming the carrier I make the outer tube, *a*, with a flange, *a'*, both in one 95 piece, and the inner tube, *b*, flush with the flange *a'*, the end of the inner tube and the flange *a'* both resting on a step or shelf formed in the outer shell of the carrier, while the diaphragm *e* is stretched across the outer end 100 of the tube *b*, and is firmly held between the surfaces of the two tubes *a* and *b* in contact. I thereby avoid a considerable expense, as the tube and flange may be spun from the same

piece of metal, and I further concentrate the weight of the metal tubes near the center of the carrier, which is an advantage, as the farther removed the weight of the metal tubes from the center the greater care must be taken to "balance" the carrier.

What I claim as my present invention, and desire to secure by Letters Patent, is—

1. The combination, with the hollow hemispheres A and B, of the outer tube, *a*, having a flange, *a'*, at one end, both in one piece, and carrying an inner tube, *b*, and elastic diaphragm *e*, outer tube, *f*, having a flange, *i*, at one end, both in one piece, and carrying an inner tube, *g*, and diaphragm *h*, the said flanges being recessed in and attached to the hemispheres A and B, as and for the purpose set forth.

2. In a hollow rolling cash-carrier formed of two parts, the locking device consisting of 20 spring-catches *c c*, recessed in one part of the carrier, and a tube projecting from the other part of the carrier, having a lip or shoulder, *f'*, with openings *j*, said projecting tube entering the recess in the opposite half of the 25 carrier, so the lip may be engaged by the spring-catches, thereby securely locking the two parts of the carrier together, as and for the purpose set forth.

JOSEPH WALTER FLAGG.
